FULL BURNER ASSEMBLY

Gilbert C. Whitney, Jr., and Kenneth E. Lee, Dansville, N.Y., assignors to Foster Wheeler Corporation, New York, N.Y., a corporation of New York
Filed Jan. 8, 1963, Ser. No. 253,781
11 Claims. (Cl. 110—28)

This invention relates to fuel burners and more particularly to fuel burner assemblies capable of controlling the direction of the flame from the nozzles of the burners.

This application is a continuation-in-part application of United States Patent applications, Serial Nos. 728,671 (now abandoned) and 847,596, filed April 15, 1958, and October 20, 1959, respectively.

Heretofore, one means for achieving control of the direction of flow of fuel from the burner nozzle, and hence, the direction of the burner flame into a combustion chamber, has been to provide burners with complex air register assemblies and actuating mechanisms for adjustment of the vanes or doors of the air registers whereby control of secondary air flow to the area of the burner nozzle outlet is effected. Another known means for achieving control of the direction of flow of fuel discharged from the burner nozzle, has been by providing the burner nozzle with a pivotal burner tip and a relatively complex burner tip actuating mechanism. The disadvantage of the foregoing burner structures is the complexity and the relatively high cost of fabrication and, in the case of the pivotal burner tip structure, control of flame direction can only be effected in one plane. A further disadvantage of present burner assemblies is the relatively large pressure drop in secondary air in flowing between the windbox and the burner nozzle outlet which necessitates the use of relatively large blowers to obtain a relatively high pressure in the windbox to compensate for the expected pressure drop at the burner nozzle outlet.

Accordingly, it is an object of the present invention to provide a relatively simple and inexpensive burner assembly wherein control of the direction of the flame burst therefrom can be achieved in a plurality of planes. Another object of this invention is to provide a burner structure wherein the pressure drop of secondary air through the burner structure is greatly minimized. A further object is to provide a burner structure having improved secondary air distribution peripherally of the burner nozzle fuel outlet whereby improved burner flame characteristics are achieved.

The present invention contemplates a novel burner assembly comprising a housing for receiving combustion air from a suitable source thereof, the housing having an outlet opening therein and a burner nozzle projecting through the outlet opening. The burner nozzle is connected at one end to receive fuel from a suitable source thereof and is provided with an outlet at the opposite end for discharging fuel for combustion. A first ring-shaped baffle or skirt is disposed in superimposed relationship over the burner nozzle and is secured to the nozzle adjacent the outlet. The baffle extends from the point of connection with the burner nozzle, through the outlet of the housing, and into the interior of the latter. A second ring-shaped baffle of larger dimensions than said first ring-shaped baffle is disposed in superimposed coaxial relationship to said first baffle. The second ring-shaped baffle is disposed to extend from a point adjacent the burner nozzle outlet into the housing outlet. Means are provided for supporting the second baffle in spaced relationship to said first baffle so that an annular combustion air passageway is defined between the baffles which passageway communicates at one end with the interior of the housing to receive combustion air and at the other end communicates with the outlet of the burner nozzle to

2

discharge combustion air peripherally of the nozzle outlet. A second means is provided for supporting and moving the second baffle relative to the first baffle to vary the axis of the flow of combustion air with respect to the longitudinal axis of the burner nozzle and flow of the fuel from the burner nozzle and thereby control the position of the burner flame produced by the combustion of fuel discharged from the burner nozzle.

As an embodiment of the invention, the secondary air 10 passageway may be defined by the outer or second ring-shaped baffle and the burner nozzle, the first ring-shaped baffle or skirt being omitted. Preferably the burner nozzle has a frusto-conical configuration, so that the passageway, as with the embodiment described above, has a long radius curvature extending from a large circumference end in communication with a source of combustion air and terminating at a small circumference end in communication with the discharge end of the burner nozzle.

Although this embodiment may result in a slightly increased pressure drop of secondary air, over the first described embodiment, it is found that the pressure drop is significantly less than with conventional assemblies, and further that a much improved distribution of secondary air peripherally of the burner nozzle discharge end is achieved, with improved burner flame characteristics and control, as with the embodiment described above.

The invention will be more fully understood from the following detailed description thereof when considered in connection with the accompanying drawings, in which:

30 FIG. 1 is a sectional view in elevation of a fuel burner assembly according to the present invention;

FIG. 2 is an end view of the fuel burner assembly of the present invention as viewed from the left in FIG. 1, with parts broken away for illustration purposes;

35 FIG. 3 is a fragmentary view in perspective showing the manner of supporting the burner assembly;

FIG. 4 is a sectional view taken substantially along line 4—4 of FIG. 1;

FIG. 5 is an enlarged fragmentary view of the support and adjustment assembly according to this invention; and

FIG. 6 is a view in section taken substantially along line 6—6 of FIG. 1.

Referring now to the drawings, 10 generally designates the burner assembly according to the invention for combustion of pulverized fuel. Burner assembly 10 is disposed exteriorly of a wall 11 of a combustion chamber (not shown) adjacent a burner port 12 provided in wall 11. The burner assembly 10 comprises a housing or windbox 13 having a top wall 14, bottom wall 15, opposite side walls 16 and 17 (FIG. 2), a rear wall 18 and a front wall 19, which walls are joined together to form a fluid-tight enclosure or plenum chamber 20. An air duct 21 is connected at one end to the bottom wall 15 of windbox 13 and at the other end to a source of secondary air under pressure (not shown), such as a fan. Flow of secondary air into chamber 20 is controlled by a damper 22 disposed within air duct 21. Front wall 19 is provided with an outlet opening 23 therein.

60 A pulverized fuel burner 24, comprising a burner nozzle 25 and a volute entrance section 26, is disposed and suitably supported in windbox 13 so that burner nozzle 25 extends horizontally through windbox outlet opening 23 to a point adjacent burner port 12. Burner nozzle 25 may be provided with spaced helical ribs on the interior surface thereof or straight ribs as disclosed in U.S. patent application Serial No. 446,532, filed July 29, 1954 now Patent No. 2,912,942 and a suitable ignitor (not shown) coaxially arranged therein. The volute section 26 is connected to a pulverized fuel and air feed pipe 27 which extends through top wall 14 of windbox 13 and is connected to a suitable source of pulverized fuel and air (not shown). The mixture of pulverized

fuel and air is fed to the volute section 25 by feed pipe 27, and thence flows through burner nozzle 25, and is discharged from the burner nozzle outlet 28 into burner port 12. Secondary air supply necessary to support efficient combustion of the fuel is delivered to the burner nozzle outlet 28, as hereinafter described.

An open-ended bell-shaped skirt or baffle 29 is disposed over and in coaxial relationship with burner nozzle 25 and is suitably secured along its smaller diameter end, as by welding at 30, to burner nozzle 25 adjacent outlet 28 of the latter. Baffle 29 is dimensioned so that it extends from its connection with the nozzle rearwardly, through outlet opening 23 in front of wall 19 of windbox 13, to a point adjacent volute section 25 and feed pipe 27. A second open-ended bell-shaped baffle 31 of substantially the same configuration as baffle 29, but of substantially larger dimensions than baffle 29, is disposed in superimposed coaxial relationship with baffle 29 and nozzle 25. Baffle 31 is dimensioned and positioned so that its smaller diameter end portion 32 projects into burner port 12 and extends rearwardly from end portion 32, through outlet opening 23 in front wall 19 of windbox 13, to a point within plenum chamber 20 adjacent the larger end of baffle 29. Baffle 31 is supported in spaced relationship to baffle 29 and nozzle 25 by support and adjustment means, hereinafter described. Baffles 29 and 31 define therebetween a secondary air passageway 33 which, as in longitudinal section has a long radius curvature. Passageway 33 communicates at one end with the interior of windbox 13 to receive secondary air from plenum chamber 20 and at the opposite end communicates with the burner nozzle outlet 28 to deliver secondary air around the periphery of nozzle outlet 28.

Baffle 29 may be provided with a plurality of spaced vanes 34, as best shown in FIGS. 1 and 6, disposed angularly around the outer surface of the baffle to impart rotational movement to the secondary air flowing through passageway 33. It has been found that imparting a small rotary movement to the flow of secondary air in the same direction as the rotational movement of the pulverized fuel and air mixture provides for the maintenance of stable ignition of the fuel.

To support baffle 31 in spaced relationship with baffle 29 and nozzle 25, baffle 31 is provided with four radially extending arms 35, 36, 37 and 38 which are spaced 90° from each other around the periphery of baffle 31. Arms 35, 36, 37 and 38 extend from baffle 31 to a point slightly beyond the plane of top wall 19, side walls 16 and 17 and bottom wall 15 of windbox 13. The distal end portions of arms 35, 36, 37 and 38 are each provided with a hole 39 which is adapted for connection to support and adjustment assemblies 40, 41, 42 and 43, respectively, hereinafter more fully described.

Burner assembly 10 is secured to combustion chamber wall 11, adjacent burner port 12, by two spaced parallel I-beams 44 and 45 which are connected to and extend horizontally between two vertically extending I-beams or buckstays 46 and 47 (FIGS. 1 and 2). As best shown in FIGS. 1 and 3, windbox 13 is secured at rear wall 18 to I-beams 44 and 45 in a suitable manner, as by brackets riveted to the beams, so that the respective legs 48 and 49 of the I-beams 44 and 45 extend, respectively, beyond the plane of top wall 14 and bottom wall 15. The opposite legs 48A and 49A of the respective I-beams 44 and 45 are also secured to a metallic ring 50 which lines the peripheral surface of a recess 51 in the exterior surface of the combustion chamber wall 11.

To seal off the space between combustion wall 11 and the windbox 13 from the air surrounding the fuel burner assembly 10, the spaces between I-beams 44, 45 and 47 and front wall 19 of the windbox is closed by an L-shaped sealing plate 47A which extends between and is welded to I-beams 44 and 45 and to the outer leg of I-beam 47, as well as to front wall 19 of windbox 13. A similar L-shaped sealing plate 46A, extends between and is

welded to I-beams 44 and 45 and outer leg of I-beam 46, to close the space between I-beams 44, 45, 46 and front wall 19 of the windbox (see FIGS. 1, 2 and 3). The space between I-beams 44, 45, and 47 and the metallic ring 50 lining recess 51 of wall 11 is closed by a plate 50A which is disposed in abutment against the inner leg of I-beam 47 and legs 48A and 49A of I-beams 44 and 45, respectively, to which legs plate 50A is welded. Plate 50A is provided with an arcuate-shaped edge portion which abuts ring 50 and is welded thereto (see FIGS. 3 and 6). A plate 50B, similar to plate 50A is welded to I-beams 44, 45 and 46 and to the metallic ring 50, in the same manner as plate 50A, to close off the space between I-beams 44, 45 and 46 and ring 50. L-shaped sealing plates 46A and 47A and plates 50A and 50B, seal off the space between windbox 13 and combustion chamber wall 11 from the surrounding air to thereby prevent secondary air leakage, through outlet 23 in front wall 19 of the windbox, to the atmosphere.

Each of the support and adjustment assemblies comprise an actuating rod 52 having a threaded end portion 53 and an opposite end portion threaded at 54. A sleeve is secured, as by welding, swaging, or the like, to each of the rods to provide an enlarged body portion 55 adjacent threaded end portion 54. The end 56 of enlarged body portion 55 adjacent end portion 54 is cut back on either side of a horizontal center line, the purpose of which will become apparent hereinafter. Each of the actuating rods 52 is provided, as best shown in FIG. 1, with a slot or keyway 52A, the purpose of which will be hereinafter explained.

Actuating rod 52 of support and adjustment assembly 40 is supported above and centrally of top wall 14 by a bearing plate 58 which is secured to top wall 14 midway between side walls 16 and 17, and by two aligned holes 59 and 60 in the respective legs 48 and 48A of I-beam 44. Bearing plate 58 is provided with a hole 61 which is adapted to receive therethrough threaded end portion 53 of actuating rod 52, while holes 59 and 60 are adapted to receive therethrough the enlarged body portion 55 of actuating rod 52. Holes 59 and 60 are so dimensioned that they are tightly embracing body portion 55 but not so tightly as to prevent axial movement of the rod therethrough. To provide additional support for rod 52, a sleeve member 62 is disposed over each of the holes 59 and 60 and is welded to the respective legs 48 and 48A of I-beam 44. Sleeve member 62 is provided with a pin 62A which extends into keyway 52A of actuating rod 52. Pin 62A and keyway 52A cooperate to prevent rotation of rod 52 and allow axial movement of the latter. End portion 54 of actuating rod 52 extends through hole 39 in arm 35 of baffle 31, and the arm is secured to the actuating rod 52 by a retaining nut 63 which is turned upon threaded end portion 54 of the rod. Nut 63 is provided with tapered inner surface 64 which is similar to the tapered end 56 of enlarged body portion 55 of actuating rod 52, so that an annular notch is defined between the latter and nut surface 64 having oppositely inclined faces which allow pivotal movement of arm 35 relative to actuating rod 52 (see FIG. 5). A handwheel 65, having an integral flanged hub 66, is turned upon threaded end portion 53 and is supported for rotation within a bearing socket member 67 which is secured to and forms a part of bearing plate 58.

To move actuating rod 52 axially within hole 61 of bearing plate 58 and holes 59 and 60 of I-beams 44, handwheel 65 is rotated upon threaded end portion 53 of the rod thereby feeding the rod toward or away from combustion wall 11, depending upon the direction of rotation of handwheel 65.

Actuating rod 52 of support and adjustment assembly 41 is supported for axial movement centrally of bottom wall 15 of windbox 13, in the same manner as actuating rod 52 of assembly 40, by a bearing plate 68, similar to bearing plate 58, and aligned holes 69 and 70 in the

respective legs 49 and 49A of I-beams 45. Rotation of rod 52 is prevented and axial movement thereof is allowed by a pin which extends into keyway 52A in the same manner as explained with respect to support and adjustment assembly 40. Actuating rod 52 of assembly 41 is also provided with a handwheel 71, similar to handwheel 65, and is connected to arm 36 of baffle 31 by a retaining nut 72 turned upon threaded end portion 54 of rod 52 in the same manner as actuating rod 52 of assembly 40 is connected to arm 35 of baffle 31.

Each of the support and adjustment assemblies 42 and 43 are supported centrally of and adjacent to side wall 16 and 17, respectively, by bearing plates 73 and 74 similar to bearing plates 58 and 68. As shown in FIG. 4, enlarged body portions 55 of actuating rods 52 of assemblies 42 and 43 are supported in holes 75 (FIG. 1) and 76 (FIG. 4), which holes are provided in L-shaped sealing plates 46A and 47A. Over each of the holes 75 and 76 is secured a sleeve 77 which is provided with a pin, similar to pin 62A which extends in keyways 52A in actuating rods 52, to prevent rotation of the rods and to permit axial movement thereof. Actuating rods 52 of support and adjustment assemblies 42 and 43 are connected, respectively, to arms 37 and 38 of baffle 31, in the same manner as actuating rods 52 of assemblies 40 and 41 are connected to arms 36 and 37, by retaining nuts 78 and 79, respectively, similar to retaining nuts 63 and 72. Actuating rods 52 of support and adjustment assemblies 42 and 43 are each provided with handwheels 80 and 81, respectively, which are supported for rotation within bearing plates 73 and 74, respectively. Axial movement of actuating rods 52 of assemblies 42 and 43 is effected by turning handwheels 80 and 81 as aforescribed with respect to actuating rods 52 of assemblies 40 and 41.

In operation of the aforescribed burner assembly 10, pulverized fuel and primary air mixture is fed to volute entrance section 26 by feed pipe 27. The mixture of pulverized fuel and primary air passes from the volute entrance section into and through burner nozzle 25. The fuel is then discharged from the burner nozzle outlet 28 into the combustion chamber (not shown) through burner port 12 in combustion chamber wall 11. Simultaneously, with the flow of pulverized fuel and air through the burner nozzle 25, secondary air under pressure is supplied to plenum chamber 20 through air duct 21. Within plenum chamber 20, the secondary air flows into annular air passageway 33 which is defined between baffles 29 and 31. The secondary air flows through passageway 33 wherein rotary motion is imparted to the air stream by action of the angularly disposed vanes 34. The air is then discharged peripherally of the burner nozzle outlet 28 into burner port 12. The pressure drop of the secondary air flow through passageway 33 is relatively small by reason of the long radius curvature of the passageway, which causes initial acceleration of air around the large circumference of the passageway, the velocity of the air stream being maintained with little pressure drop through the passageway. However, there is sufficient pressure drop to insure uniform distribution of secondary air in plenum chamber 20 to achieve uniform peripheral distribution of air into annular passageway 33. By reason of the long radius nozzle configuration of passageway 33, a more uniform distribution of air at the burner nozzle outlet 28 is achieved and, hence, improved flame character. The annular long radius nozzle configuration of passageway 33 also minimizes unnecessary and unsymmetrical air turbulence and therefore only a small degree of movement of baffle 31 relative to nozzle 25 is necessary to effect a change in the direction of the flame. Further improved flame character and stability of the flame is achieved by vanes 34 which impart rotation to the air stream through passageway 33 in the same direction as the rotation of the primary air and fuel mixture passing through nozzle 25.

Change in the direction of flow of fuel from burner nozzle outlet 28, and thereby the direction of the flame in

the combustion chamber, may be effected by moving baffle 31 relative to baffle 29 and burner nozzle 25 through adjustment of one or more of the actuating rods 52 of support and adjustment assemblies 40, 41, 42 and 43 to cause the off-axial positioning of baffle 31 relative to the axes of baffle 29 and nozzle 25. As illustrated in FIG. 1, if it is desired to direct the flame downwardly into the combustion chamber, handwheel 65 is rotated on threaded end portion 53 of actuating rod 52 of assembly 40 to cause the actuating rod to move axially toward the combustion chamber wall 11 to a position shown by the broken line, while handwheel 71 of assembly 41 is rotated to cause actuating rod 52 to move axially in a direction away from wall 11. Movement of actuating rods 52 of assemblies 40 and 41 carries arms 35 and 36 of baffle 31 respectively toward and away from the combustion chamber wall 11 to the positions shown by the broken lines thereby tilting baffle 31 so that baffle 31 within plenum chamber 20 abuts baffle 29, as is also shown by the broken lines in FIG. 1. With baffle 31 positioned as shown in broken lines of FIG. 1, the axis of baffle 31 is changed so that the mass of secondary air flowing through passageway 33 enters the furnace along an axis which is at an angle with respect to the axis of the primary air and pulverized fuel flow mixture discharging from nozzle 25 thereby causing the flame burst to assume an axis or direction which is at a downward angle with respect to the axis of nozzle 25.

To direct the fuel stream and, therefore, the flame burst upwardly, handwheel 65 is turned so as to retract actuating rod 52 past the original position shown in full lines, while handwheel 71 of support and adjustment assembly 41 is turned so as to move its actuating rod 52 toward combustion chamber wall 11. Axial movement of the actuating rods carries arm 36 toward wall 11 and arms 35 away from wall 11 thereby tilting baffle 31 so that its axis extends upwardly relative to the axes of baffle 29 and burner nozzle 25. In this position, the axis of baffle 31 is changed so that the mass of secondary air flowing through passageway 33 enters the furnace along an axis which is at an upward angle with respect to the axis of the primary air and fuel mixture discharging from nozzle 25 thereby causing the flame burst to assume an axis or direction which is at an upward angle with respect to the axis of nozzle 25.

In the same manner as aforescribed, the fuel and primary air stream discharged from burner nozzle 25 may be directed in a horizontal plane to the right or left of the burner nozzle axis by effecting a tilting of baffle 31 relative to baffle 29 and burner nozzle 25 through turning handwheels 80 and 81 of support and adjustment assemblies 42 and 43.

If it is desired to direct the fuel and primary air stream in a direction lying in both a vertical and horizontal plane with respect to the axis of burner nozzle 25, adjustment is effected of either actuating rod 52 of assemblies 40 and 41, depending on whether it is desired to direct the flame above or below the axis of burner nozzle 25, and assemblies 42 or 43, depending on whether it is desired to direct the flame to the right or left of the axis of burner nozzle 25.

By relative adjustment of assemblies 40, 41, 42 and 43 baffle 31 may be tilted in any direction with respect to baffle 29 and burner nozzle 25 and to any degree between extreme positions thereof whereby precise directional control of the flame burst can be achieved.

It should be apparent that the above support and adjustment assemblies effect a movement of the outer baffle 31 about an imaginary pivot point approximately located in the plane of the burner nozzle outlet and along the longitudinal axis of the nozzle to position the axis of the baffle at an angle relative to the burner nozzle axis. In this way control of the direction of the burner flame is achieved with optimum distribution of secondary air peripherally around the burner nozzle outlet. In par-

ticular, the dimensions of the passageway annularly about the nozzle are uniformly maintained, avoiding constricting the passageway in a manner adjacent the outlet to adversely affect flame characteristics. This is particularly important when it is realized that the flow rate of the secondary air is approximately 40 times by weight that of the primary air flow.

It has been found that the angle of change of baffle 31 relative to nozzle 25 achieves an angle of change in the direction of the burner flame which is substantially the same as that of the angle of change of baffle 31 and therefore only a small angular movement of baffle 31 is needed to effect the same degree of flame direction that is obtained by a conventional pivotal burner tip.

It can be seen readily from the foregoing description that a novel burner assembly has been provided wherein directional control of the flame burst can be achieved through 360° around the axis of the burner nozzle without expensive or complicated structures. It is a burner assembly wherein the pressure drop through the burner is greatly reduced so that windbox pressure need not be as high as in conventional intervane type burner assemblies.

It is to be understood that while the burner assembly 10 of the present invention has been illustrated and described as adapted for burning pulverized fuel, the invention is not limited thereto. The invention is applicable to burners constructed for burning gaseous fuel, liquid fuels and the like, without departure from the spirit and scope of the invention.

Although but one embodiment of the invention has been illustrated and described in detail, it is to be expressly understood that the invention is not limited thereto.

For example, the involute section need not be disposed within the windbox but may be positioned outside of the rear wall of the windbox with the burner nozzle extending through the rear wall. In addition, the windbox may be secured directly to the outer surface of the combustion chamber wall.

Further, referring to FIG. 1, it is evident that the baffle or bell-shaped skirt 29 may be omitted so that the passageway is defined by the burner nozzle 25 and the outer bell-shaped baffle 31. Preferably, the burner nozzle will have a frusto-conical configuration such that the secondary air passageway extends, with, substantially, a large radius curvature, from a large circumference end in communication with a source of combustion air to a small circumference end in communication with the discharge end of the burner nozzle. The outer baffle, pivoting about a point located approximately in the plane of the burner nozzle outlet and along the axis of the nozzle, effectively directs the combustion air and controls the direction of the burner flame. This is accomplished without constricting the passageway around the burner nozzle outlet and with a uniform distribution of secondary air and a uniform velocity pattern around the nozzle.

In certain installations, it may be desirable to position the burner nozzle as far away from radiation as is practical without impairing the operation of the burner. In these cases, the pivot point for the baffle may be slightly in front of the burner nozzle but along the axis of the nozzle, the important factor being that the baffle should be pivoted in a manner so that the velocity pattern around the burner remains substantially uniform. A uniform velocity in the annulus around the nozzle is essential to achieve a uniform dispersion rate of fuel in the secondary air stream and a well-shaped flame.

Other variations can be made in the arrangement of parts, as will be understood by those skilled in the art, without departing from the spirit and scope of the invention as described in the following claims.

What is claimed is:

1. A fuel burner assembly comprising, a burner nozzle having a longitudinal axis connected to receive fuel from

5 a source thereof and having an outlet to discharge the same for combustion, a source of combustion air under pressure, a baffle arrangement including at least one tubular member encompassing the burner nozzle and coaxial therewith arranged to define with the nozzle an elongated annular passageway of diminishing circumference, said passageway extending from a large circumference end in communication with said source of combustion air to receive combustion air and terminating at a small circumference end in communication with the discharge end of said burner nozzle to discharge combustion air adjacent said burner nozzle outlet, said member being pivotally adjustable about a point approximately located in the plane of the burner nozzle outlet and along the axis of the nozzle to position the axis of said member at an angle relative to the longitudinal axis of the burner nozzle to vary the direction of the combustion air discharged and to control the direction of the burner flame, and means to pivotally adjust said member.

10 2. A fuel burner assembly according to claim 1 wherein said burner nozzle is provided with a frusto-conical configuration the small diameter end of which defines the burner nozzle outlet, said tubular member being bell-shaped such that the passageway defined by the burner nozzle and said member has substantially a long radius curvature.

15 3. A fuel burner assembly comprising, a burner nozzle having a longitudinal axis connected to receive fuel from a source thereof and having an outlet to discharge the same for combustion, a source of combustion air under pressure, a baffle arrangement including a pair of substantially coaxial tube-like baffles encompassing the burner nozzle and arranged to define an elongated surrounding passageway of diminishing circumference, said passageway extending from a large circumference end in communication with said source of combustion air to receive combustion air and terminating at a small circumference end in communication with the discharge end of said burner nozzle to discharge combustion air adjacent said burner nozzle outlet, the outer of said coaxial baffles being pivotally adjustable about a point approximately located in the plane of the burner nozzle outlet and along the axis of the nozzle to position the axis of the outer coaxial baffle at an angle relative to the longitudinal axis of the burner nozzle thereby varying the direction of the combustion air discharge and controlling the direction of the burner flame, and means to pivotally adjust said outer baffle.

20 4. A burner assembly, comprising a windbox having an inlet to receive combustion air and having an outlet opening therein, a fuel injector nozzle having a longitudinal axis, an inlet to receive fuel and an outlet to discharge said fuel for combustion, said nozzle being disposed with a portion thereof extending through the outlet of said windbox and with the outlet of said nozzle being outside of said windbox, a ring member disposed over said nozzle and secured to said nozzle adjacent the outlet of the latter, said ring member flaring outwardly from the point of connection with the nozzle to a point within the outlet opening of said windbox, a ring-shaped baffle disposed in superimposed spaced relationship with said ring member and flaring outwardly from a point adjacent the outlet of said nozzle to a point within the outlet opening of said windbox, said ring member and said baffle defining therebetween an elongated annular combustion air passageway having a long radius curvature extending from and communicating with the interior of said windbox to receive combustion air from the latter and terminating adjacent the outlet of said nozzle to discharge combustion air around the nozzle outlet, and means for pivotally moving the baffle about a point approximately located in the plane of the injector nozzle outlet and along the axis of the nozzle relative to said ring member and nozzle to obliquely position the axis of said baffle relative to the axes of the latter thereby varying the direction of the com-

bustion air discharged and controlling the direction of the burner flame.

5. A burner assembly, comprising a windbox having a combustion air inlet and outlet opening, a fuel injector nozzle having a longitudinal axis, an inlet to receive fuel and an outlet to discharge said fuel for combustion, said nozzle being disposed with a portion thereof extending through the outlet of said windbox with the outlet of said nozzle being outside of said windbox, a bell-shaped ring member disposed over and in coaxial relationship with the injector nozzle, said bell-shaped ring member being connected at the smaller diameter end to said nozzle at a point adjacent the outlet of the latter and extending in a direction away from the outlet of the nozzle through the outlet opening of the windbox to a point within the windbox, a second bell-shaped ring member of larger dimensions than said first-mentioned ring member disposed in a substantially coextensive superimposed coaxial relationship with said first-mentioned ring member, said second bell-shaped ring member extending from the smaller diameter end thereof from a point adjacent the outlet of said nozzle through the inlet of said windbox to a point within said windbox, means for supporting the second bell-shaped ring member in spaced relationship to said first-mentioned bell-shaped ring member and said nozzle whereby an elongated annular combustion air passageway having a long radius curvature is defined between the bell-shaped ring members, said combustion air passageway communicating with the interior of the windbox to receive combustion air and terminating adjacent the outlet of the nozzle, and adjusting means for pivotally moving said second bell-shaped ring member about a point approximately located in the plane of the injector nozzle outlet and along the axis of the nozzle relative to said first mentioned bell-shaped ring member and the nozzle to obliquely position the axis of the second bell-shaped ring member relative to the axes of the latter thereby varying the direction of the combustion air discharged and controlling the direction of the burner flame.

6. The apparatus of claim 5 wherein the support means comprises a plurality of four equally spaced arms which are secured to the second bell-shaped ring member and extend radially therefrom and wherein adjusting means comprises a rod for each of said arms, each rod being connected to the distal end portion of an arm, and each of said rods being mounted for axial movement to effect tilting movement in any plane of the second bell-shaped ring member relative to said first mentioned bell-shaped ring member.

7. A pulverized fuel burner comprising a windbox having an inlet for receiving secondary air and an outlet, a pulverized fuel injector assembly having a longitudinal axis, an involute portion and a discharge nozzle portion, said involute portion being connected to receive a mixture of primary air and pulverized fuel and connected to said discharge nozzle portion to pass said mixture of primary air and pulverized fuel to said nozzle for discharge, said fuel injector assembly being disposed with the involute portion within the windbox and the discharge nozzle projecting through the outlet of said windbox, a ring member having an open end portion adapted to receive therethrough said discharge nozzle and an opposite open end portion of substantially larger dimension than said first mentioned open end portion, said ring member being disposed over said discharge nozzle of said pulverized fuel injector assembly and secured at the smaller open end portion to said discharge nozzle adjacent the outlet thereof and with the larger open end portion projecting into the interior of the windbox, a baffle means of substantially the same configuration as said ring member and of larger dimensions than the latter being disposed in a substantially coextensive superimposed spaced relationship with said ring member to define with the latter an elongated annular secondary air passageway, said baffle means and said ring member being formed so that the annular secondary air

passageway has a long radius curvature, said passageway communicating at one end with the interior of said windbox to receive secondary air therefrom and terminating at the opposite end adjacent the discharge end of said nozzle, means for tilting said baffle about a point approximately located in the plane of the discharge nozzle outlet and along the axis of the nozzle relative to said ring member to vary the direction of the combustion air flow discharged from said air passageway with respect to the longitudinal axis of said burner nozzle to thereby controllably vary the direction of the flame produced by the combustion of the fuel discharged from said burner nozzle.

8. In combination with a furnace wall having a burner port therein, a burner disposed adjacent the outer surface of said furnace wall comprising a windbox having an inlet to receive combustion air and an outlet, a fuel injector nozzle having a longitudinal axis, an inlet to receive fuel and an outlet to discharge fuel for combustion, said nozzle being disposed with a portion thereof extending through the outlet of said windbox and terminating adjacent the burner port to discharge fuel into the latter, an open-ended bell-shaped member disposed over and in coaxial relationship with the injector nozzle, said bell-shaped member being connected at the smaller diameter end to said nozzle at a point adjacent the outlet of said nozzle, and extending in a direction away from the nozzle outlet through the outlet opening of the windbox to a point within the windbox, a second open-ended bell-shaped member of larger dimensions than said first-mentioned bell-shaped member disposed in superimposed, coaxial relationship with said first-mentioned bell-shaped member and with the smaller diameter end portion disposed in the burner port in sealing contact therewith but arranged for pivotal movement relative to the axis of the burner port, said second bell-shaped member extending from the burner port through the outlet of said windbox to a point within said windbox, means for supporting said second bell-shaped member in spaced relationship to said first-mentioned bell-shaped member so that an elongated annular combustion air passageway is defined between the two bell-shaped members, the wall of each of said bell-shaped members having a long radius curvature so that said annular passageway has a long radius curvature, said passageway communicating at the large circumference end with the interior of the windbox to receive combustion air from the latter and at the opposite small circumference end communicating with the burner port to discharge combustion air therein adjacent the outlet of the injector burner nozzle, and other means for pivotally moving said second bell-shaped member about a point approximately located in the plane of the injector nozzle outlet and along the axis of the nozzle relative to said first-mentioned bell-shaped member and the injection nozzle to obliquely position the axis of said second member relative to the axes of the latter thereby varying the direction of the combustion air discharged and controlling the direction of the burner flame.

9. The apparatus of claim 8 wherein a plurality of spaced vanes are disposed in said annular combustion air passageway to impart rotary motion to the combustion air flowing through said air passageway.

10. The apparatus of claim 8 wherein said first-mentioned means comprises a plurality of spaced arms radially extending from said second bell-shaped member and said other means comprises a plurality of rods mounted on said windbox for axial movement, one rod connected at one end to an arm whereby relative axial movement of said rods effects through said arms movement of said second bell-shaped member relative to said first mentioned bell-shaped member.

11. In combination with a furnace wall having a burner port therein, a pulverized fuel burner comprising a windbox having an inlet to receive secondary air and an outlet adjacent said burner port, a burner nozzle having a longi-

tudinal axis, an inlet to receive a mixture of pulverized fuel and primary air and an outlet to discharge said fuel and air mixture, said burner nozzle being disposed to project through the windbox outlet toward said burner port, a ring member disposed around said nozzle and connected to said nozzle adjacent the outlet of the latter, said ring member extending from the point of connection with the nozzle outwardly from the nozzle and into the windbox through said outlet of the windbox, a ring-shaped baffle of substantially the same configuration as said ring member and of larger dimensions than the latter being disposed in superimposed spaced relationship with the ring member and extending from a point adjacent said nozzle outlet into said windbox, the wall of each of said ring-shaped baffle and ring member having a long radius curvature so that an elongated annular combustion air passageway having a long radius curvature is defined between the walls of said ring-shaped baffle and ring member, said passageway being in communication at the large circumference end with the interior of said windbox to receive secondary air therefrom and at the opposite small circumference end communicating with the area adjacent the outlet of said nozzle to discharge secondary air pe-

ripherally of said nozzle outlet, and means for tilting the ring-shaped baffle about a point approximately located in the plane of the burner nozzle outlet and along the axis of the nozzle relative to said ring member to vary the direction of the secondary air flow discharged from said annular secondary air passageway with respect to the longitudinal axis of the burner nozzle to thereby controllably vary the direction of the flame produced by the combustion of fuel discharged from the burner nozzle.

UNITED STATES PATENT OFFICE
CERTIFICATE OF CORRECTION

Patent No. 3,143,089

August 4, 1964

Gilbert C. Whitney, Jr., et al.

It is hereby certified that error appears in the above numbered patent requiring correction and that the said Letters Patent should read as corrected below.

In the heading to the drawings, Sheets 1 to 4, line 2 thereof, and in the heading to the printed specification, line 2, title of invention, for "FULL BURNER ASSEMBLY", each occurrence, read -- FUEL BURNER ASSEMBLY --.

Signed and sealed this 20th day of April 1965.
